UNITED STATES PATENT OFFICE.

HERBERT A. WALLACE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed June 14, 1926. Serial No. 115,831.

My invention relates to railway traffic controlling apparatus of the type comprising train carried governing means controlled by code impulse combinations supplied to the trackway.

I will describe one form of railway traffic controlling apparatus embodying my invention, and will then point out the novel features thereof in claims.

10 In the accompanying drawings, Fig. 1 is a diagrammatic view illustrating one form of railway traffic controlling apparatus embodying my invention. Fig. 2 is a view showing, partly in front elevation and partly in vertical section, the selector comprising a portion of the railway traffic controlling apparatus embodying my invention. Fig. 3 is a sectional view along lines III—III of Fig. 2. Fig. 4 is a view partly diagrammatic, showing the contact structure of the selector illustrated in Figs. 2 and 3. Fig. 5 is a sectional view along the lines V—V of Fig. 4.

Similar reference characters refer to similar parts in each of the several views.

Referring first to Fig. 1, the reference characters 1 and 1^a designate the track rails of a stretch of railway track. The rails are supplied with code impulse combinations by a transmitter J which as here shown comprises a rotatable shaft 12 driven by a synchronous motor M supplied with energy from an alternator G.

The shaft 12 operates a plurality of transmitting commutators, each designated by the reference character H with a distinguishing exponent, and each comprising a conducting disk 13 rigidly attached to the shaft 12 and having a brush designated by the reference character E with a suitable exponent bearing on the edge of the disk. The edge of each disk is provided with a plurality of segments 15 of equal and comparatively small peripheral lengths and a single segment 14 of comparatively large peripheral length, the segments being defined by insulating blocks 16 inserted in the disks 12. It will be noted that the segments 15 for all the commutators are of the same size but that the segments 14 increase progressively in size from commutator H³ to commutator H⁶.

A circuit controller 20, operated in any suitable manner, is arranged to connect al-

ternator G across the rails 1 and 1^a through any selected one of the commutators H. For example, when contact 20—K³ is closed, current flows from alternator G, through shaft 12, disk 13 of commutator H³, brush E³, and contact 20—K³ to rail 1, and from rail 1^a directly back to alternator G. When this circuit is closed, an impulse of alternating current is supplied to the rails each time a segment 15 or 14 engages brush E³, the length of each impulse being determined by the length of the segment engaging the brush. Although I do not wish to limit myself to any particular time elements, for purposes of explanation I will assume that the impulse of energy delivered to the track rails when the brush engages a segment 15 contains five alternations of the current supplied by alternator G, and that the impulse delivered to the rails when segment 14 engages the brush contains fifteen complete alternations or three times the number of the alternations in the impulse due to the shorter segments. For reasons which will appear hereinafter, I shall call the shorter impulses of five alternations each, "holding impulses," and I shall call the longer impulses of fifteen alternations each, "coding impulses."

In similar manner when contact 20 engages any of the other contacts K, current from alternator G is supplied to the track rails by the associated commutator H in the form of code impulse combinations each comprising a coding impulse followed by a number of holding impulses each two impulses being separated by a time interval. The holding impulses for the various code impulse combinations are all of the same length, but the coding impulses for each such combination are of different lengths for different commutators, and in the form here shown the parts are proportioned so that the exponent of the reference character H for each commutator indicates the multiple of the length of the holding impulse represented by the coding impulse for that commutator. Thus the coding impulse delivered to the rails when commutator H⁷ is transmitting is seven times the length of the holding impulses or thirty-five alternations.

The train T is provided with apparatus which is selectively responsive to the code impulse combinations supplied to the track-

100

105

way by the transmitter J. This apparatus comprises two magnetizable cores 32 and 32^a carried by the train in advance of the forward axle 31 and located in inductive relation with the two track rails 1 and 1^a respectively. Core 32 is provided with a winding 33 and core 32^a is provided with a winding 33^a, the two windings 33 and 33^a being connected in series in such manner that the voltages induced therein by alternating current flowing in opposite directions in the track rails at an instant are additive. The windings 33 and 33^a are connected through amplifying apparatus D with one magnet A of the selector shown in Figs. 2 and 3. The primary of transformer Q is connected in parallel with magnet A and the secondary of this transformer supplies energy to a magnet C.

Referring now to Figs. 2 and 3, the selector comprising the two magnets A and C as here shown is similar to the cycle counting selector disclosed in my co-pending application, Serial No. 14,941, filed March 12, 1925, for code signaling apparatus but this particular form of selector is not essential to my invention. This selector comprises a plunger 5 provided with an armature 4 controlled by the magnet A. Journalled at 6, in the top of the plunger 5, is a spindle 7 which carries a disk B biased by means of a spring 8 to the position shown in the drawing in which position a projection 17 engages a fixed stop 26. A toothed wheel 10 is located above the disk B co-axial therewith and is arranged to be stepped around in a counter clockwise direction as viewed in Fig. 3 by means of a pawl 11 controlled by magnet C. When magnet A is de-energized, plunger 5 occupies its lower position in which it is illustrated in the drawing and the disk B therefore occupies its initial position under the influence of spring 8. When magnet A is energized, however, armature 4 is drawn upwardly, raising the plunger 5, and lifting disk B into engagement with wheel 10. If wheel 10 is stepped around by the pawl 11 due to energization of magnet C by alternating current when disk B is in its upper position, the disk is carried in a counter clockwise direction (Fig. 3). If now magnet A becomes de-energized, the plunger 5 drops, disengaging the disk B from the wheel 10 and allowing the spring 8 to return to its initial position. The frictional engagement of the wheel and the disk may be increased by a washer 23.

In addition to the projection 17, disk B is provided with two other spaced projections 18 and 19, which are arranged to co-operate with certain fixed contact fingers located adjacent the edge of the disk B. Referring now to Fig. 4, the selector is provided with a series of contact fingers each designated by the reference character N with a distin-

guishing exponent, for co-operation with projection 17. In similar manner, the projection 18 co-operates with a series of contact fingers O, and projection 19 co-operates with a series of contact fingers P. The disk 70 B also carries a finger 21 which is arranged at times to engage a fixed segment 22.

In explaining the operation of the apparatus, I will assume that contact 20—K³ is closed so that code impulse combinations are supplied to the track rails by commutator H³ of transmitter J. At the instant the commutator H³ is in the position shown in the drawing the segment 14 is entering into engagement with the brush E³. A coding impulse is therefore supplied to the track rails. This impulse, through the medium of the pick-up apparatus on the train T and the amplifier D, energizes magnet A, lifting disk B into engagement with wheel 10. At 75 the same time, alternating current supplied to magnet C from transformer Q steps the wheel 10 in a counter clockwise direction by an amount which depends upon the number of complete alternations in the coding impulses. When disk B is moved to its upper position the projections 17, 18 and 19 are lifted above the plane of the associated fingers N, O and P, and contact 21 is also lifted above the plane of the segment 22, so that 80 during this motion, no contact is closed by the selector. When the wheel 10 is stepped around by the coding impulse supplied by commutator H³, the projection 17 will be 85 above the plane of the segment 22, so that during this motion, no contact is closed by the selector. When the wheel 10 is stepped around by the coding impulse supplied by commutator H³, the projection 17 will be 90 above the plane of the segment 22, so that 95 during this motion, no contact is closed by the selector. When the wheel 10 is stepped around by the coding impulse supplied by commutator H³, the projection 17 will be 100 above the plane of the segment 22, so that 105 during this motion, no contact is closed by the selector. When the segment 14 passes off of the brush E³ at the end of the coding impulse, the interruption of the current supplied to the track rails will de-energize magnet A so that disk B will drop to its lower position. During this motion of the disk, contact 17—N³ and contact 21—22 are both 110 closed momentarily. When the disk is in its lower position, however, the contacts are 115 open and will remain open as the disk returns to its initial position. During the brief interval that contact 17—N³ is closed, however, a surge of energy is supplied from a suitable source, such as a battery 24, to relay U. Similarly, the momentary closing of contact 21—22 completes a circuit for 120 relay S. Relays S and U both become energized. It should be noted that when relay S is energized, a stick circuit for relay U is closed over front contact 27 of relay S. As the transmitter J continues to operate, 125 the first segment 15 of commutator H³ engages brush E³ to supply a holding impulse to the trackway. This holding impulse causes the disk B to be lifted, and stepped around to a position indicated by the character 1 in Fig. 4. At the end of the hold- 130

ing impulse the disk B drops to its lower position, thereby closing contact 21-22. But contact 17-N³ is not closed because the length of the holding impulse is not sufficient to step the disk far enough to move projection 17 over finger N³. At the end of the holding impulse, however, the closing of contact 21-22 supplies a surge of energy to relay S. This relay is therefore again energized. For each of the succeeding holding impulses supplied to the trackway during the code impulse combination transmitted by commutator H³, relay S receives a surge of energy. Due to the slow-acting characteristics of this relay, the front contact 27 of the relay remains closed during the brief interval separating successive holding impulses. As long as front contact 27 is closed, the stick circuit for relay U is also closed, this circuit having been completed at front contact 28 of relay U when this relay was first energized by the coding impulse. After relay U is once picked up by the coding impulse, this relay is maintained in its energized condition as long as relay S is held in its energized condition by the intermittent energization resulting from successive holding impulses. When the commutator H³ is moved to a position in which segment 14 again engages brush E³, a coding impulse is supplied to the selector which again supplies energy directly to relay U over contact 17-N³. Subsequently, the holding impulses supplied to the trackway, resulting in the continued energization of relay S, maintain relay U in its energized condition.

I will now assume that contact 20-K⁴ is closed so that code impulse combinations are supplied to the track rails from commutator H⁴. The coding impulse of each code impulse combination is now longer than when current is being supplied over commutator H³ so that during this impulse, projection 17 moves past finger N³ to the position indicated by the character 4. Projection 18 will then occupy a position over contact O⁴ and finger 21 will also be over the segment 22. At the end of the coding impulse, when disk B drops to its lower position, contact 21-22 and contact 18-O⁴ are momentarily closed, but contact 17-N³ is not closed. Relay S therefore receives a surge of energy as before, but current is supplied from battery 24 to relay V instead of to relay U. The energization of relay V with relay S energized completes a stick circuit for relay V over its own front contact 29, and front contact 27 of relay S. As the operation of transmitter J continues, the intermittent energization of relay S holds the front contact of this relay closed so that relay V is maintained in its energized condition as long as relay S is energized.

In similar manner if contact 20-K⁵ is

closed so that commutator H⁵ supplies code impulse combinations to the trackway, the disk B will be stepped around during the coding impulse to a position in which projection 17 occupies the position indicated by the character 5. Projection 19 will then be located over contact finger P⁵ so that when the disk B drops to its lower position at the end of the coding impulse contacts 21-22 and 19-P⁵ are closed momentarily so that a surge of energy is delivered to relay W, energizing this relay and completing a stick circuit for this relay over its own front contact 30 and front contact 37 of relay S. During the subsequent holding impulses the continued energization of relay S maintains relay W in its energized condition by virtue of its stick circuit so that the relay W is energized as long as relay S is energized.

When contact 20-K⁶ is closed so that commutator H⁶ supplies code impulse combinations to the trackway the disk B is stepped around during each coding impulse to a position in which projection 17 is over finger N⁶ as indicated by the character 6. When the disk is in this position, projection 18 is also located over contact finger O⁶ so that when the disk drops to its lower position at the end of the coding impulse, contact 17-N⁶ and contact 18-O⁶ are both closed in addition to the closing of contact 21-22. Surges of energy are therefore supplied simultaneously to relays S, U and V and relays U and V are both maintained in their energized condition by virtue of their stick circuits as long as relay S is subsequently held closed by holding impulses supplied from the trackway.

In similar manner, when commutator H⁷ is transmitting code impulse combinations, contacts 21-22, 17-N⁷ and 19-P⁷ will be momentarily closed at the expiration of each code impulse so that relays S, U and W will be energized. When commutator H⁸ is supplying code impulse combinations to the trackway the contacts 21-22, 18-O⁸ and 19-P⁸ will be momentarily closed at the end of each code impulse and relays S, V and W will be energized. Finally, when commutator H⁹ is supplying code impulse combinations to the trackway, the disk B will be stepped around during each coding impulse to a position in which projection 17 is located above contact finger N⁹, as indicated by the character 9. When the disk drops to its lower position at the end of the coding impulse, contacts 17-N⁹, 18-O⁹, and 19-P⁹ are all closed in addition to the closing of contact 21-22 so that under this condition all of the relays S, U, V and W are energized. It should be pointed out that when code impulse combinations are being supplied to the trackway by any of the commutators H the contact 21-22 is closed for each operation of the selector for either cod-

ing impulses or holding impulses so that for each impulse supplied to the trackway, a surge of energy is supplied to relay S, but that the remaining relays receive energy only during the coding impulses.

It will be observed that on each commutator the insulating block 16^a which engages the associated brush E immediately before the corresponding segment 14 is longer than the remaining insulating blocks 16. As a result of this construction the time interval between the last holding impulse of each code impulse combination and the coding impulse of the succeeding combination is longer than the other time intervals. During this longer interval, the train carried relays are all de-energized and the proper relay or relays are again picked up by the coding impulse for the next combination as explained hereinbefore. The purpose of this arrangement is to insure that when one of the commutators H is disconnected and another commutator supplies a new code impulse combination, only the train carried relay or relays which should be energized by the coding impulse of the new combination will be energized.

The relays U, V and W may be used to control governing means on the train in any suitable manner, such for example, as shown in my co-pending application for Letters Patent of the United States, Serial No. 681,742, filed Dec. 20, 1923, for railway traffic controlling apparatus.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. Railway traffic controlling apparatus comprising means for supplying the trackway with energy in the form of coding impulses separated by time intervals during which the trackway is supplied with holding impulses, train carried means responsive to the lengths of said coding impulses, and other means on the train responsive to said holding impulses for controlling said train carried means.

2. Railway traffic controlling apparatus comprising means for supplying the trackway with code impulse combinations each comprising a coding impulse and at least one holding impulse, a train carried relay, means responsive to said coding impulse but not to said holding impulse to energize said relay, and means responsive to said holding impulse for subsequently maintaining said relay in its energized condition.

3. Railway traffic controlling apparatus

comprising means for supplying the trackway with different code impulse combinations each comprising a coding impulse and at least one holding impulse, the coding impulses being of different lengths for different code impulse combinations, a plurality of train carried relays, means responsive to the lengths of such coding impulses for energizing a selected one or ones of said relays, and means responsive to said holding impulse for subsequently maintaining such selected relay or relays in energized condition.

4. In combination, a selector, means for supplying the selector with code impulse combinations each comprising a coding impulse and at least one holding impulse, a plurality of relays, means controlled by said selector for selectively energizing said relays in accordance with the length of said coding impulse, and means also controlled by said selector and responsive to said holding impulse for maintaining such relays in their energized condition.

5. In combination, a source of code impulse combinations each comprising a coding impulse and at least one holding impulse, a selector controlled by energy received from said source and comprising a plurality of contacts selectively operated in accordance with the length of said coding impulses, an additional contact operated when either said coding impulses or said holding impulse are supplied to the selector, and governing means controlled jointly by said contacts.

6. In combination, a source of code impulse combinations each comprising a coding impulse and at least one holding impulse, a selector controlled by energy received from said source and comprising a plurality of contacts selectively operated in accordance with the lengths of said coding impulses, an additional contact operated when either said coding impulses or said holding impulse are supplied to the selector, a first relay controlled by said additional contact, and a plurality of relays all controlled in part by said first relay and each controlled in part by one of said plurality of contacts on said selector.

7. In combination, a source of code impulse combinations each comprising impulses of different lengths, a plurality of relays, means controlled by energy received from said source and responsive to the length of one impulse of each said combination for energizing a selected one of said relays, and means responsive to the other impulses of each combination for subsequently maintaining said selected one of such relays in its energized condition.

8. In combination, a source of code impulse combinations each comprising impulses of different lengths, a plurality of relays, a selector controlled by energy received

- from said source and responsive to the length of each impulse, means controlled by said selector for energizing a selected one of said relays according to the length of one impulse of each combination, and means also controlled by said selector and responsive to the lengths of the other impulses in each code impulse combination for subsequently maintaining said selected relay in its energized condition. 50
9. In combination, a source of code impulse combinations each comprising impulses of different lengths, a plurality of relays, means controlled by the first impulse of each combination for energizing a selected one of said relays in accordance with the length of said impulse, and means controlled by the remaining impulses of each combination for subsequently maintaining said selected relay in its energized condition. 55
10. In combination, with a source of alternating current, means for interrupting current from said source to form code impulse combinations each comprising impulses of different lengths, a plurality of relays, means controlled by the first impulse of each combination for energizing a selected one of said relays in accordance with the number of alternations in such impulse, and means controlled by the remaining impulses in each said combination and responsive to the number of alternations in such remaining impulses for subsequently maintaining such selected relay in its energized condition till the end of such code impulse combination. 60
11. In combination, a source of code impulse combinations, each comprising impulses of different lengths, a selector controlled by energy received from said source and responsive to the number of alternations in each impulse, a plurality of relays, means controlled by said selector and responsive to the number of alternations in the first impulse of each combination for 65
- energizing a predetermined one of such relays, and means responsive to the number of alternations in the remaining impulses of said combination for maintaining such predetermined relay in its energized condition, all said relays becoming de-energized at the end of each code impulse combination. 70
12. In combination, a stretch of railway track, means for supplying alternating current to the rails of said stretch and for periodically interrupting such supply to provide code impulse combinations each comprising a coding impulse of one length and holding impulses of a different length, said coding impulses being of different lengths for different codes, a selector controlled by current in the track rails and comprising a plurality of contacts one or another of which is momentarily closed after each impulse 75
- depending upon the number of alternations in the impulse, a plurality of train carried relays, means controlled by said contacts for energizing a selected one of said relays after each coding impulse depending upon which contact closes, means for supplying a surge of energy to another relay during each holding impulse, and means for subsequently maintaining such selected relay in its energized condition as long as such other relay is energized. 80
13. Railway traffic controlling apparatus comprising means for at times supplying the trackway with code impulse combinations each comprising impulses of different lengths and for at other times supplying the trackway with code impulse combinations each comprising impulses of different lengths and at least one of which is of different length from a corresponding impulse of said first code impulse combinations, and train carried governing means selectively responsive to the lengths of such impulses. 85
- In testimony whereof I affix my signature.

HERBERT A. WALLACE.
